CLAIM

The ornamental design for pants with elastic leg cuffs for easy insertion into boots, as shown and described.

DESCRIPTION

FIG. 1 is a perspective view of a first embodiment of pants with elastic leg cuffs for easy insertion into boots, showing my new design;

FIG. 2 is a front elevation thereof;

FIG. 3 is right side elevation view thereof, the left side being a mirror image thereof;

FIG. 4 is a rear elevation thereof;

FIG. 5 is a front elevation view thereof, shown in use condition;

FIG. 6 is a perspective view of a second embodiment of pants with elastic leg cuffs for easy insertion into boots, showing my new design;

FIG. 7 is a front elevation thereof;

FIG. 8 is right side elevation view thereof, the left side being a mirror image thereof;

FIG. 9 is a rear elevation thereof; and,

FIG. 10 is a front elevation view thereof, shown in use condition.

The broken line in the figure drawings represents unclaimed environment only and forms no part of the claimed design.
